UNITED STATES PATENT OFFICE.

RICHARD A. STRATTON, OF PHILADELPHIA, PENNSYLVANIA, ASSIGNOR TO
G. W. CARR & CO., OF SAME PLACE.

IMPROVEMENT IN JOINTS FOR RIBS OF UMBRELLAS AND PARASOLS.

Specification forming part of Letters Patent No. 36,260, dated August 19, 1862.

To all whom it may concern:

Be it known that I, RICHARD A. STRATTON, of Philadelphia, Pennsylvania, have invented an Improvement in Joints for the Ribs and Stretchers of Umbrellas and Parasols; and I do hereby declare the following to be a full, clear, and exact description of the same, reference being had to the accompanying drawings, and to the letters of reference marked thereon.

My invention relates to the joints which connect the stretchers to the ribs of an umbrella or parasol; and my invention consists of a metal block cast to each rib and arranged for connection to the stretcher in the manner described hereinafter, so as to form a cheap and durable joint without weakening the rib at the point where the greatest strength is required.

In order to enable others skilled in the art to make and use my invention, I will now proceed to describe the manner of carrying it into effect.

On reference to the accompanying drawings, which form a part of this specification, Figure 1 is a perspective view of my improved joint for the ribs and stretchers of umbrellas and parasols, and Fig. 2 is a diagram illustrating the manner of making that part of the joint which is attached to the rib.

On reference to Fig. 1, A represents a portion of one of the steel-wire ribs of an umbrella or parasol, and B a portion of the wire stretcher joined to the rib.

The stretcher has the forked end with which usual metal stretchers are provided, and in this forked end fits a block, D, attached to the rib A, in the manner described hereinafter, a pin or rivet passing through the fork and the block, and thus completing the joint.

In constructing the joints of metal ribs and stretchers it has been usual to pierce the rib for the admission of the pin or rivet, or else to bend the rib in such a manner as to form an eye on the same. In the former case the rib is necessarily weakened at the point where the greatest strength is required, and in the latter case the metal wire is necessarily deteriorated by the abrupt bends to which it is subjected in order to produce the eye. Discarding both of these plans, I cast the block D of metal directly onto the rib at the desired point; a slight indentation having been made in the

wire, so that the metal block will retain its proper position on the rib; or, in place of indenting the rib, it may be tinned at the point where the block has to be secured, thus insuring a thorough union of the molten metal with the steel rib.

In order to cast the block onto the rib I make use of the well-known type-molding machine, which will be sufficiently understood by reference to Fig. 2. E represents the reservoir containing the metal of which the block D has to be made; F, the chamber for containing the fire, the latter maintaining the metal in a molten state, and G the chimney.

By means of a lever, H, and plunger I, a portion of the molten metal is forced into a space inclosed by two dies, K and K', this space being of the exact form of the block D, and the rod A having been previously passed through the dies at the proper point, so that the moment the plunger I is operated the molten metal will surround and adhere to the rod, and a block, D, of the desired form will be produced.

The hole in the block for the reception of the pin may be drilled or punched, or it may be made during the process of casting by passing a pin of proper size through the dies at the desired point and subsequently withdrawing the pin.

The metal used for forming the block may be ordinary type-metal, or any other metal or alloy of sufficient durability may be used.

It will be evident without further description that joints thus constructed for ribs and stretchers of umbrellas and parasols may be made cheaply and rapidly, and without weakening the rib A at the point where the greatest strength is required.

Without claiming, broadly, the casting of one metal onto another, I claim as my invention, and desire to secure by Letters Patent, as a new manufacture—

The block D, cast to the rib A, and arranged for connection to the stretcher B, as and for the purpose herein set forth.

In testimony whereof I have signed my name to this specification in the presence of two subscribing witnesses.

RICHARD A. STRATTON.
